UNITED STATES PATENT OFFICE.

EDMOND GREGORY O'DONNELL, OF FALL RIVER, MASSACHUSETTS,
ASSIGNOR, BY DIRECT AND MESNE ASSIGNMENTS, TO AMERICAN
HAT SWEAT SEWING MACHINE COMPANY, OF FALL RIVER, MASSA-
CHUSETTS, A CORPORATION OF MAINE.

COMBINED PRESSER-FOOT AND NEEDLE-BAR LIFTING MECHANISM FOR SEWING-MACHINES.

SPECIFICATION forming part of Letters Patent No. 709,354, dated September 16, 1902.

Application filed April 22, 1901. Serial No. 56,940. (No model.)

To all whom it may concern:

Be it known that I, EDMOND GREGORY O'DONNELL, a citizen of the United States, and a resident of Fall River, in the county 5 of Bristol and State of Massachusetts, have invented a new and Improved Combined Presser-Foot and Needle-Bar Lifting Mechanism for Sewing-Machines, of which the following is a full, clear, and exact description.
10 This invention relates to a mechanism especially intended for use in connection with machines for sewing sweat-bands into hats, although it obviously may be used on other machines if desired.
15 The object is to provide means whereby upon the movement of the presser-bar the needle-bar will be disconnected from its driving mechanism and lifted to a height sufficient to bring the point of the needle above the 20 bottom of the presser-foot when the presser-foot is at its highest position. In the practical machine the presser-foot is arranged to rise about one inch above the needle-plate, and if the needle is raised to the elevation of 25 the presser-foot it is clear that work even of such a cumbersome nature as a stiff felt hat may be readily placed in and out of position, owing to the fact that when the needle-bar is thus lifted and is disconnected from its 30 driving mechanism there is no danger of accidentally starting the needle while the work is being placed into or displaced from the machine, since when the needle is thus raised the drive-shaft of the machine may be freely 35 turned without affecting the needle-bar. By lowering the presser-foot the needle drops into position and is automatically connected to its driving mechanism.

This specification is a specific description 40 of one form of the invention, while the claims are definitions of the actual scope thereof.

Reference is to be had to the accompanying drawings, forming a part of this specification, in which similar characters of reference indicate corresponding parts in all the views.
45

Figure 1 is a sectional elevation of the invention on the line 1 1 of Fig. 2. Fig. 2 is a front elevation of the mechanism, showing

the presser-bar and other parts broken away. Fig. 3 is a horizontal section on the line 3 3 50 of Fig. 1. Fig. 4 is a fragmentary side view of the two arms of the machine. Fig. 5 is a view similar to Fig. 1, except that the parts are in different positions. Fig. 6 is a detail view of the thread-controller; and Figs. 7, 8, 55 and 9 are reduced front elevations of the mechanism, respectively showing it in operative position, in half-raised position, and in full-raised position.

10 indicates the upper arm of the machine, 60 and 11 the lower arm. This lower arm is preferably, though not necessarily, provided with shield and guide devices, such as described in my copending application for hat-sewing machines, filed April 22, 1901, Serial No. 65 56,941.

18 indicates the needle-bar, and 17 the presser-bar, which are carried to move vertically through the casing 35 at the outer end of the arm 10.

70
36 indicates the drive-shaft, which extends horizontally through the upper arm 10. This drive-shaft carries loosely a pinion-gear 37, and on this pinion-gear is suitably fastened a crank-arm 38, swinging with the pinion-gear around the axis of the shaft 36. The crank 38 is joined by a link 39 to the needle-bar 18, and upon the rocking of the shaft 36 reciprocal movement will be imparted to the needle-bar through the medium of the parts 37, 38, and 39, provided said gear 37 is fast to its shaft. Clutch mechanism is provided for rendering said gear fast or loose on the shaft, as desired, and this clutch mechanism comprises a disk or key-holder 40, which carries one or more pins or keys 41, these pins being fastened to or formed integral with the key-holder as desired.

80
42 indicates a collar keyed on the shaft 36 and through which collar the pins or keys 40 90 project, said pins extending beyond the collar into engagement with suitable orifices in the gear 37.

43 indicates a rod fast to the key-holder 40 and projected into the tubular end of the shaft 95 36, and 44 indicates a spring, which holds

the key-holder 40 and its pin removably in the position shown in Fig. 3. When the clutch devices are in the adjustment shown in this view, the gear 37 is fast to the shaft 36, and therefore the needle is in positive connection with its driving mechanism. When the key-holder 40 is drawn out, as shown in Fig. 5, and its pins disengaged from the gear 37, the gear is then loose on the shaft 36, and the rocking of this shaft will not influence the parts 37, 38, and 39.

A yoke or cap 45 incloses the key-holder 40 and is connected therewith by pins 46, running in an annular groove in the key-holder or clutch-disk 40. This cap 45 is connected to one arm of a bell-crank lever 47, and against the diagonal edge 48 of the other arm of said bell-crank lever runs a roller 49, carried on the arm 50 of the presser-bar yoke. The other arm 51 of the yoke projects through a vertical slot in the casing 35 and carries a roller 52, under which bears the lifting-lever 53, (see Fig. 2,) such lever being adapted to be connected with a treadle or knee-brace device, so as to exert an upward pressure on the arm 51 of the yoke, thus raising the presser-bar. 54 indicates a hand-cam, which bears under the lifting-lever 53, and which may be used instead of the lifting-lever as desired. When the presser-bar and its yoke, the latter comprising the parts 50 and 51, are raised, the roller 49 rides against the inclined surface 48 of the bell-crank lever 47 and throws the lever from the position shown in Fig. 1 to that shown in Fig. 5, thus drawing outward the key-holder or clutch-disk 40 and disengaging the pins or keys 41 from the gear 37 and crank 38. This operation is effected and the parts assume the position shown in Fig. 5 when the presser-bar is half-raised. (See Fig. 8.) The further upward movement of the presser-bar continues without influencing the lever 47, except to hold it in the position shown in Fig. 5. From this time on the needle-bar is disconnected from its driving mechanism; but the needle-bar does not begin to move until the parts assume the position shown in Figs. 5 and 8.

The gear 37 is meshed with a toothed sector 55, the radius of which is greater (preferably twice) than that of the gear 37. This sector 55 is mounted idly on the wall of the casing 35, within the casing, and when the needle-bar is in operation under the action of the shaft 36 the toothed sector 55 plays idly around its pivot. The toothed sector 55 is provided with an antifriction-roller 56, and this roller is adapted to be engaged by an extension 57 of the arm 50 of the presser-bar yoke. This engagement of the parts 57 and 56 does not take place until the clutch is disconnected—that is to say, until the presser-bar has performed one-half of its upward movement and the parts assume the position shown in Figs. 5 and 8. At this period the continued upward movement of the extension 57 of the

presser-bar yoke imparts a like movement to the toothed sector 55, and owing to the ratio between the gears 55 and 37 the gear 37 is turned at a greater speed than that of the movement of the toothed sector. Upon the rotation of the gear 37 under the action of the sector 55 the crank 38 and link 39 act quickly to raise the needle-bar, carrying it from its uppermost operating position (see Figs. 7 and 8) to its uppermost position. (See Fig. 9.) The presser and needle bars reach this uppermost position simultaneously, the presser-bar moving slowly and the needle-bar starting after the movement of the presser-bar, but moving rapidly to overtake it. The upward movements of the bars cease when the point of the needle is raised clear of the bottom of the presser-foot. The presser-bar 17 is pushed downward by a spring 58 and the parts will automatically return to their lower position (see Fig. 7) under the action of the spring when contrary pressure on the presser-bar is not exerted. The hand-cam 54 is formed with a shoulder which will serve to hold the presser-bar raised against the action of this spring 58, and therefore the parts will remain in this upper position (see Fig. 9) until the hand-cam 54 is thrown downward into operative position, or, if the action be brought about by the lifting-lever, until pressure on the lifting-lever is relaxed. Now it is clear that owing to the comparatively great movement of the presser-foot and needle and to the fact that the needle rises fully as high as the presser-foot the work may be easily inserted into the machine or removed from it, and there is no danger of prematurely starting the action of the needle-bar, owing, for instance, to the accidental starting of the shaft 36 or its connected parts. 59 indicates a thread-controlling device. (See Figs. 2 and 6.) This device forms no part of the present invention, but is merely illustrated to show the position of the other parts with respect to it.

Various changes in the form and details of my invention may be resorted to at will without departing from the spirit of my invention. Hence I consider myself entitled to all forms of the invention as may lie within the intent of my claims.

Having thus described my invention, I claim as new and desire to secure by Letters Patent—

1. In a sewing-machine, the combination with the needle and presser bars, of means for driving the needle-bar, said means including a clutch, and a device in connection with the clutch and with the needle-bar and actuated from the presser-bar, said device serving first to disconnect the clutch and then raise the needle-bar.

2. In a sewing-machine, the combination with the needle and presser bars, of a driving mechanism for the needle-bar, such mechanism including a clutch, and means for dis-

connecting the clutch and raising the needle-bar, said means being actuated from the presser-bar.

3. In a sewing-machine, the combination 5 with the needle and presser bars, of a driving mechanism for the needle-bar, said mechanism including a clutch, a lever in connection with the clutch, a yoke connected with the presser-bar and engaging the lever to 10 throw open the clutch, and a member engaged and moved by the yoke upon the opening of the clutch, such member having connection, with the needle-bar, to raise it.

4. In a sewing-machine, the combination 15 with the needle-bar of means for driving the same, said means including a clutch, and manually-operative devices in connection with the clutch and with the needle-bar, said devices serving first to disconnect the clutch, 20 second to raise the needle-bar.

5. In a sewing-machine, the combination with the needle and presser bars, of means for driving the needle-bar, and means acting first to disconnect the needle-bar-driving 25 means, and second to raise the needle-bar, said latter means being fastened to the presser-bar to be actuated therefrom.

6. In a sewing-machine, the combination with the drive-shaft and with the needle and 30 presser bars, of a gear loose on the drive-shaft, a toothed sector meshed with the gear, a cranked connection between the gear and needle-bar, a clutch for fastening the gear to the drive-shaft, and a member connected with 35 the presser-bar, said member acting first to disengage the clutch, and second, to throw the toothed sector.

7. In a sewing-machine, the combination with the drive-shaft and with the needle and 40 presser bars, of a gear loose on the drive-shaft, a toothed sector meshed therewith, a cranked connection between the needle-bar and the gear, a clutch connecting the gear with the drive-shaft, an elbow-lever in connection with 45 the clutch, and a yoke carried by the presser-bar, said yoke serving first to throw the elbow-lever and next to swing the sector.

8. In a sewing-machine, the combination with the drive-shaft and needle and presser 50 bars, of a gear loose on the drive-shaft, a collar fastened to the drive-shaft, a clutch-disk or key-holder having a key or pin movable loosely through the collar and into engagement with the gear to fasten the gear to the shaft, a cranked connection between the gear and the needle-bar, a toothed sector meshed with the gear, a lever having connection with the key-holder, and a yoke carried on the presser-bar and engaging first the lever and then the toothed sector.

9. In a sewing-machine, the combination with the needle and presser bars and the drive-shaft, of a gear loose thereon, a cranked connection between the gear and the needle-bar, 65 a toothed sector meshed with the gear, a collar fast on the drive-shaft adjacent to the gear,

a key-holder having a pin or key movable loosely through the collar and into engagement with the gear, a yoke or cap with which the key-holder is connected to rotate, a lever 70 in connection with the cap, and means operated from the presser-foot for throwing first the lever and then the sector.

10. In a sewing-machine, the combination with the needle and presser bars and the drive-shaft, of a gear loose thereon, a cranked connection between the gear and the needle-bar, a toothed sector meshed with the gear, a collar fast on the drive-shaft adjacent to the gear, 75 a key-holder having a pin or key movable 80 loosely through the collar and into engagement with the gear, a yoke or cap with which the key-holder is connected to rotate, a lever in connection with the cap, and means operated from the presser-foot for throwing first 85 the lever and then the sector, said lever being of elbow form and having a diagonally-disposed surface on one arm to be engaged by said yoke of the presser-bar.

11. In a sewing-machine, the combination 90 with the needle and presser bars and the drive-shaft, of means for driving the needle-bar from the drive-shaft, said means including a clutch, an elbow-lever connected with the clutch and having on one arm a diagonal or 95 cam surface, and a yoke carried by the presser-bar and arranged first to engage said diagonal surface of the elbow-lever and throw the same, thus disconnecting the clutch, and second, to impart a rising movement to the needle-bar.

12. In a sewing-machine, the combination with the needle and presser bars and with the drive-shaft, of means for driving the needle-bar from the shaft, said means including a 105 clutch, a member movably connected with said means to impart a rising movement to the needle-bar, an elbow-lever connected with the clutch to operate it, the said elbow-lever having on one arm a diagonal or cam surface, 110 and a yoke carried by the presser-bar and arranged to engage said diagonal surface of the elbow-lever and then to move the said member for lifting the needle-bar.

13. In a sewing-machine, the combination 115 with the needle and presser bars and with the tubular drive-shaft, of a gear loose on the drive-shaft, a cranked connection between the gear and needle-bar, a collar fast to the drive-shaft, a key-holder having a key sliding loosely through the collar and engageable with the gear, a rod attached to the key-holder and passing into the tubular portion of the shaft, a spring within the shaft, the spring pressing on the rod to hold the key-holder in 120 active position, a cap with which the key-holder has rotary connection, means for moving the cap outward to disengage the pin or key from the gear without interfering with the rotary movement of the shaft and the 125 parts directly attached thereto, a toothed sector meshed with the loose gear, and a means

actuated from the presser-bar for throwing the sector.

14. In a sewing-machine, the combination with the needle-bar of means for driving the same, said means including a clutch, a spring holding the clutch yieldingly in active position, and manually-operative devices in connection with the clutch and with the needle-

bar, said devices serving first to disconnect the clutch, second to raise the needle-bar.
